FIG. 1

FIG. 2

FIG. 3

FIG. 4

FIG. 5

FIG. 6

FIG. 7

FIG. 1 is a front elevation of a key holding attachment for a key case, the end hook members being swiveled in an upward position, the others in a depending storing position, and the conventional key case being shown in broken lines for illustrative purposes;

FIG. 2 is an enlarged elevational view of one of the key holding members of FIG. 1;

FIG. 3 is a side elevational view of FIG. 2 as seen from the right;

FIG. 4 is a top plan view of FIG. 2;

FIG. 5 is a bottom plan view of FIG. 2, the hook member being sectioned below the holder bottom for convenience of illustration;

FIG. 6 is a side elevational view of FIG. 2 as seen from the left, the hook being fragmentarily shown for convenience of illustration; and

FIG. 7 is a perspective view of FIG. 2, the hook being fragmentarily shown.

The essential features of the design reside in the full line showing of the key holder members, the key case shown in broken lines being of conventional configuration.

We claim:

The ornamental design for a key holding attachment for key cases, as shown and described.
